UNITED STATES PATENT OFFICE.

ALFRED G. F. KUROWSKI, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed March 19, 1921. Serial No. 453,616.

To all whom it may concern:

Be it known that I, ALFRED G. F. KUROWSKI, a citizen of the United States, residing in Brooklyn Borough, in the county of 5 Kings, city and State of New York, have invented certain new and useful Improvements in Typewriting Machines, of which the following is a specification.

This invention relates to typewriting machines, and, more particularly, to means for rapidly advancing a work-sheet forwardly around the platen a predetermined distance.

The invention is especially adapted to expedite the introduction of work-sheets to 10 locate them in a uniform, first writing line, position. Means are therefore provided by this invention for rapidly rotating the platen forwardly by a single stroke of an operating handle through a predetermined 15 distance. A multiplying gearing between the operating handle and the platen shaft permits a rapid movement of the platen, so that, as the handle reaches its limiting position, a possible overthrow of the platen, 20 due to its momentum, may result. It is a feature of this invention to provide a positive stop for the platen to prevent such overthrow. It is a further feature of this 25 invention to provide limiting stops for the operating handle which are easily and conveniently settable. Still another feature of 30 this invention is to provide such an arrangement of parts as to allow for the easy and convenient adjustment and assembling of 35 the various parts.

Other features and advantages will hereinafter appear.

In the accompanying drawings,

Figure 1 is a plan view of a machine with 40 the invention applied thereto, only the necessary co-operating elements being shown.

Figure 2 is an end view of the device shown in Figure 1, the operating handle being in its rearward position.

Figure 3 is a view similar to Figure 2, 45 the operating handle being shown in its forward, or operated, position.

Figure 4 is a detail sectional view of the adjustable stop.

Figure 5 is a detail perspective view of 50 the member in which the adjustable stop is slidable, showing also the pawl-releasing cam or projection.

Figure 6 is a vertical section of the in-

vention as applied to an end wall of the 55 platen-frame.

A rotary platen 1 is fixed to an axle 2 journaled in the end walls 3, 4 of a platen-frame 5. The platen may be rotated by hand-wheels or knobs 6 fixed on the ends 60 of the platen axle, or by the usual line-space mechanism, comprising a line-space wheel 7 fixed to the platen axle and adapted to be rotated by a pawl 8 pivoted on a slide 9 driven by a line-space lever 10. Work-sheets are fed over a rear paper-table 11 beneath the platen, to which they are held by the usual front and rear feed-rolls 13 and 14, and upwardly to the printing point indicated by the type-head 12 in Figure 3. 70

As hereinbefore set forth, the work-sheet or web may comprise a series of similar forms adapted to be typed in succession, the distance from the last typed line on one form to the first line to be typed on the 75 next form being constant. During the typing operation, the platen may be line-spaced by the finger-wheels 6 or the usual line-space mechanism operated by the lever 10. When a form has been typed, however, and 80 it is necessary to rotate the platen to the first line on the next form, it is desirable to perform this rotation quickly. For this purpose, there is fixed to one of the end walls of the platen-frame, here shown as 85 the right wall 4, a bracket 20 having a vertical wall 21 in contact with the end wall 4, and a horizontal flange 22 overlying the top-plate 23 of the end wall and fastened thereto by screws 24. Spaced from the 90 bracket 20 by studs 31 is a plate 30, fixed to said studs by screws 32. The vertical wall 21 of the bracket 20 is provided with a hub 33. A stub-shaft 34 passes through plate 30 and is journaled in said hub at one end, 95 said end being grooved at 35 to provide a seat for a set-screw 36 which fastens the stub-shaft in any desired position.

Upon the stub-shaft 34 there are mounted, between the end of hub 33 and plate 30, 100 a ratchet-wheel 40, to which is fixed a gear-wheel 41, and a stop-lever 42 connected to the stub-shaft by a hub 43. Said ratchet and gear-wheel run idly on the stub-shaft while the stop-lever is loosely rotatable on 105 said shaft. The hubs 33 and 43 and the ratchet and gear-wheels substantially fill the space between the bracket 20 and plate

30. Gear-wheel 41 meshes with a gear-wheel 44 fixed to the platen axle 2 which projects through plate 30. The lever-arm 42 is bent at 45 to overlie the gear-wheel 5 44 and is provided with a tooth 46 which engages gear-wheel 44 when arm 42 is depressed. Arm 42 is normally maintained in elevated position by a spring 47 fixed to a pin 48 on the arm and to a pin 49 on the 10 bracket.

On the outer side of plate 30 there are loosely mounted on the stub-shaft a handle 51 and a combined stop-gage and pawl-releasing means 52, said handle and gage 15 being held in place by a nut 53 screwed on the end of the stub-shaft. Pivoted on the handle 51 by a stud 60 is a pawl 54 overlying the ratchet-wheel 40 and pressed normally toward the ratchet-wheel by a 20 spring 55 engaging pins 56 and 57 on the pawl and handle, respectively. A hub 61 is screwed on the other end of stud 60 and encloses spring 55 and pins 56 and 57. The rearward movement of the handle 51 25 is limited by the contact of hub 61 with a horizontal projection 62 on the stop-gage. The latter may be adjusted to various positions as will be described hereinafter. In 30 the final portion of the rearward movement of handle 51, a pin 63 on pawl 54 is engaged and has its rearward movement arrested by a ledge 65 of said stop-gage 52, thus causing the pawl 54 to be swung out of 35 engagement with the ratchet-wheel 40 against the action of spring 55. To allow for the pivotal movement of pawl 54, pin 56 operates in an arcuate slot 58 in handle 51.

Upon forward movement of handle 51, pin 63 will ride off ledge 65, allowing the pawl to engage ratchet-wheel 40 and rotate it forwardly. Since gear 41 is fixed to the ratchet-wheel, it will rotate therewith, rotating gear-wheel 44, and hence the platen, 45 a greater distance and at a greater speed, depending upon the ratio of gear-wheels 41 and 44. This ratio can be any desired amount, depending upon the amount of platen rotation desired, the latter in turn 50 depending upon the bills or forms used. As shown, the ratio of the wheels 41 and 44 is two to one, so that half a revolution of the handle 51 will produce one complete revolution of the platen. Since the speed 55 of rotation of the platen is multiplied, there would be a tendency for the platen to overthrow, i. e., run past the predetermined stopping point, due to its momentum. To prevent such overthrow, the pawl 54 is provided with a pin 70 which seats in a depression 71 in the stop-lever 42 when the forward movement of the handle is almost completed. Further movement of the handle will force tooth 46 of the stop-lever 60 between two adjacent teeth of the gear- 65

wheel 44 and prevent further rotation of said wheel, and hence of the platen. A positive stop is therefore provided for the handle at the end of its forward movement. As the handle moves rearwardly, spring 70 75 lifts tooth 46 out of engagement with gear-wheel 44, and pawl 54 rides idly over the teeth of ratchet-wheel 40 until it is lifted out of contact therewith by cam 64 to ledge 65. To return the handle automatically to its rearward position, there is provided a spring 75 fixed to the stub-shaft 34 and to a pin 76 on handle 51. The pin 76 operates in a slot 77 in plate 30, and the spring is housed in a recess 78 in the body 80 of the ratchet-wheel 40. Forward movement of handle 51 winds up the spring, which returns the handle to its rearward position when the operator releases the handle. The tension of the spring may be 85 adjusted by loosening screws 36 and turning the stub-shaft.

The forward limiting position of the handle 51 is invariable, occurring when the handle presses tooth 46 into mesh with 90 wheel 44. To allow for rotation of the platen through variable distances, the stop-gage 52 is made adjustable. The stop-gage may be rotated about its pivot 80 to vary the position of the horizontal projection 62 engaged by the handle. The gage is fixed in an adjusted position by a spring 81 co-operating with any one of a series of holes 82 in plate 30. Since the ratio of gear 41 to gear 44 has been assumed 95 to be two to one, one revolution of the ratchet-wheel will yield two revolutions of the platen. Since a complete revolution of the platen corresponds to thirty-three line-spaces, a complete revolution of the ratchet-wheel will correspond to sixty-six line-spaces. The ratchet-wheel is therefore provided with sixty-six teeth on its periphery, each tooth corresponding to a line-space. Provision is made for fixing the stop-gage 100 105 110 115 in various positions, each position corresponding to a difference of one line-space from the preceding or succeeding position. For this purpose, the plate 30 is provided with holes arranged in staggered relation in two concentric rows to prevent crowding. To enable the spring plunger 81 to co-operate with either row, a cover plate 83, fixed to plunger casing 84, is attached by screws 85 to a block 86 slidable laterally 120 in opening 87 of the stop-gage. A flange 88 on block 86 operates in a groove 89 adjacent the opening 87 on the inner face of the gage, thus guiding the movement of the block. 125

The operation of the device will be apparent from the above description, but is briefly as follows: Spring plunger 81 is pulled out clear of the openings in plate 30, and the stop-gage is set a number of line- 130

spaces back of its forward limiting position equal to the number of line-spaces between the last typed line of a form and the first line to be typed on the next form.

5 The spring plunger having been set in the adjusted position, the handle 51 is rotated rearwardly until hub 61 rests on projection 62 of the stop-gage. The form is typed, being line-spaced by the usual line-space 10 lever 10, or by knobs 6, gear-wheels 41 and 44 meshing without affecting handle 51, since the pawl 54 is out of engagement with ratchet-wheel 40. When the last line of the form has been typed, handle 51 is swung 15 forwardly against the action of spring 75 which winds up, and pin 63 rides off ledge 65, allowing the pawl to engage the ratchet-wheel. Further forward rotation of the handle produces a forward rotation of the 20 platen until pin 70 engages in depression 71 in the stop-lever 42, forcing tooth 46 between adjacent teeth on wheel 44 and preventing any further forward rotation of the platen. Spring 75 will return handle 51 to 25 its rearward position, pin 63 riding up cam-surface 64 until it rests on ledge 65, thus withdrawing the pawl from engagement with the ratchet-wheel.

Variations may be resorted to within the 30 scope of the invention, and portions of the improvements may be used without others.

Having thus described my invention, I claim:

1. In a typewriting machine having a 35 revoluble platen, line-space mechanism for advancing the platen by steps of definite extent, a platen-sweeping handle and rotation-multiplying connections between the handle and the platen, in combination, a pivotally-mounted stop for limiting the travel of the handle to control the extent of the platen-sweeping movement, and means for adjusting the stop to any one of a large number of positions, comprising a plate having a 40 plurality of rows of holes so arranged that the travel of the handle can be varied by steps of line-space extent, and a latch slidably mounted on the stop for movement along the stop toward and from the pivot 45 of the stop into position to enter any one of said holes to detain the stop in the adjusted positions determined by the holes.

2. In a typewriting machine having a 50 revoluble platen, line-space mechanism for advancing the platen by steps of definite line-space extent, a platen-sweeping handle and rotation-multiplying connections between the handle and the platen, in combination, a pivotally-mounted stop for determining a limiting position of the platen-sweeping handle to control the extent of its 55 operative movement, and means for adjusting said stop, comprising a plate having a plurality of arcuate rows of holes coaxial 60 with the handle and so arranged that the

travel of the handle can be adjusted to any whole number of line-spaces, and a stop-adjusting device consisting of a slide mounted on the adjustable stop and movable therewith toward and from the pivot of the 70 handle, and a manually-operable spring-plunger carried by the slide and movable therewith into position to co-operate with any one of said holes.

3. In a typewriting machine, the combination with a platen-frame, a platen-shaft journaled therein and carrying a platen, and a regular line-space mechanism for said platen, of a gear fixed to said shaft, an auxiliary platen-turning mechanism mounted on said frame and comprising a second gear meshing with said first gear, a ratchet-wheel fixed to said second gear, an operating handle, and a pawl on said handle engageable with said ratchet-wheel when said handle is operated forwardly to rotate said platen, and a positive stop for limiting the forward rotation of said platen, said stop comprising a lever pivotally mounted on said frame and engageable by said pawl, 80 said lever having means at one end adapted to mesh with said first gear when said pawl engages said lever to prevent further rotation of the platen.

4. In a typewriting machine, the combination with a platen-frame, a platen-shaft journaled therein and carrying a platen, and a regular line-space mechanism for said platen, of a gear fixed to said shaft, an auxiliary platen-turning mechanism mounted 100 on said frame and comprising a second gear meshing with said first gear, a ratchet-wheel fixed to said second gear, an operating handle, and a pawl on said handle engageable with said ratchet-wheel when said handle is 105 operated forwardly to rotate said platen, a positive stop for limiting the forward rotation of said platen, said stop comprising a lever pivotally mounted on said frame and engageable by said pawl near the end of the 110 forward movement of the operating handle, and having means at one end adapted to mesh with said first gear upon further movement of said handle to prevent further rotation of the platen, and a spring fixed at one 115 end to said frame and at the other end to said lever and normally maintaining the means at the end of said lever out of mesh with said first gear.

5. In a typewriting machine, the combination with a platen-frame, a platen journaled therein, and a regular line-space mechanism for said platen, of an auxiliary platen-turning mechanism comprising a gear connected to rotate the platen, a ratchet-wheel 120 fixed to said gear, an operating handle, and a pawl on said handle engageable with said ratchet-wheel when said handle is operated forwardly to rotate said platen, means for limiting the forward movement of said han- 125

- idle, a shaft journaled in said handle and carrying a hub at one end, said pawl being fixed to the other end of said shaft, a spring within said hub connected at one end to said pawl and at the other end to said handle and normally pressing said pawl into engagement with said ratchet-wheel, and a member comprising a combined stop-gage for limiting the rearward movement of said handle and pawl-releasing means to disengage said pawl from said ratchet-wheel before the handle reaches its rearward limit, said stop-gage comprising a horizontal projection of said member in the path of said hub, said hub contacting with said projection to limit the rearward movement of said handle.

6. In a typewriting machine, the combination with a platen-frame, a platen journaled therein, and a regular line-space mechanism for said platen, of an auxiliary platen-turning mechanism comprising a gear connected to rotate the platen, a ratchet-wheel fixed to said gear, an operating handle, and a pawl on said handle engageable with said ratchet-wheel when said handle is operated forwardly to rotate said platen, a pin carried by said pawl, a positive step for limiting the forward rotation of said platen, said stop comprising a lever pivotally mounted on said frame and engageable by the pin on said pawl, a second pin carried by said pawl, and a member comprising a combined stop-gage for limiting the rearward movement of said handle and pawl-releasing means engageable by said second pin to disengage said pawl from said ratchet-wheel before the handle reaches its rearward limit.

7. In a typewriting machine, the combination with a platen-frame, a platen journaled therein, and a regular line-space mechanism for said platen, of an auxiliary platen-turning mechanism comprising a gear connected to rotate the platen, a ratchet-wheel fixed to said gear, an operating handle, and a pawl on said handle engageable with said ratchet-wheel when said handle is operated forwardly to rotate said platen, means for limiting the forward movement of said handle, a stub-shaft fixed to said frame and upon which said auxiliary platen-turning mechanism is rotatably mounted, said ratchet-wheel having a recess in its surface, a spring housed in said recess and connected to said shaft at one end and to said handle at the other end for opposing said forward movement and maintaining said handle normally in a rearward position, and a stop-gage for limiting the rearward movement of said handle.

8. In a typewriting machine, the combination with a platen-frame, a platen journaled therein, and a regular line-space mechanism for said platen, of an auxiliary platen-turning mechanism comprising a gear connected to rotate the platen, a ratchet-

wheel fixed to said gear, an operating handle, and a pawl on said handle engageable with said ratchet-wheel when said handle is operated forwardly to rotate said platen, means for limiting the forward movement of said handle, a stub-shaft fixed to said frame and upon which said auxiliary platen-turning mechanism is rotatably mounted, said ratchet-wheel lying adjacent said plate on one side thereof, said handle rotating adjacent said platen on the other side thereof, said ratchet-wheel having a recessed portion adjacent said platen, and a spring housed in said recessed portion between said ratchet-wheel and said plate and connected to said shaft at one end and to said handle at the other end for opposing said forward movement and maintaining said handle normally in a rearward position.

9. In a typewriting machine, the combination with a platen-frame, a platen journaled therein, and a regular line-space mechanism for said platen, of an auxiliary platen-turning mechanism comprising a gear connected to rotate the platen, a ratchet-wheel fixed to said gear, an operating handle, and a pawl on said handle engageable with said ratchet-wheel when said handle is operated forwardly to rotate said platen, means for limiting the forward movement of said handle, a plate fixed to and spaced from said frame, a stub-shaft fixed to said frame and projecting through said plate and upon which said auxiliary platen-turning mechanism is rotatably mounted, said ratchet-wheel lying adjacent said platen on one side thereof, said handle rotating adjacent said platen on the other side thereof, said ratchet-wheel having a recessed portion adjacent said platen, a spring housed in said recessed portion between said ratchet-wheel and said plate, said plate having a segmental slot, and a pin fixed to said handle and projecting through said slot, said spring being connected to said pin at one end and to said shaft at the other end for opposing said forward movement and maintaining said handle normally in a rearward position.

10. In a typewriting machine, the combination with a platen-frame, a platen journaled therein, and a regular line-space mechanism for said platen, of an auxiliary platen-turning mechanism comprising a gear connected to rotate the platen, a ratchet-wheel fixed to said gear, an operating handle, and a pawl on said handle engageable with said ratchet-wheel when said handle is operated forwardly to rotate said platen, means for limiting the forward movement of said handle, a stub-shaft fixed to said frame and upon which said auxiliary platen-turning mechanism is rotatably mounted, said ratchet-wheel lying adjacent said platen on one side thereof, said handle rotating adjacent said platen on the other side thereof, said ratchet-wheel having a recessed portion adjacent said platen, a spring housed in said recessed portion between said ratchet-wheel and said plate, said plate having a segmental slot, and a pin fixed to said handle and projecting through said slot, said spring being connected to said pin at one end and to said shaft at the other end for opposing said forward movement and maintaining said handle normally in a rearward position.

platen-turning mechanism is rotatably mounted, said ratchet-wheel having a recess in its surface, a spring housed in said recess and connected to said shaft at one end and 5 to said handle at the other end for opposing said forward movement and maintaining said handle normally in a rearward position, a stop-gage for limiting the rearward movement of said handle, and means 10 whereby said shaft may be adjusted to vary the tension of said spring.

11. In a typewriting machine, the combination with a platen-frame, a platen journaled therein, and a regular line-space mechanism for said platen, of an auxiliary platen-turning mechanism comprising a gear connected to rotate the platen, a ratchet-wheel fixed to said gear, an operating handle, and a pawl on said handle engageable with said ratchet-wheel when said handle is operated forwardly to rotate said platen, means for limiting the forward movement of said handle, a hub on said frame, a stub-shaft journaled in said hub 25 at one end, said auxiliary platen-turning mechanism being rotatably mounted on said shaft, said ratchet-wheel having a recess in its surface, a spring housed in said recess and connected to said shaft at one end and to 30 said handle at the other end for opposing said forward movement and maintaining said handle normally in a rearward position, said shaft being rotatable in said hub to vary the tension of said spring, and 35 means passing into said hub and engaging said shaft for fixing said shaft in position.

12. In a typewriting machine, a rotary platen, and means for effecting and determining a gross line-spacing movement thereof, comprising a gear connected to rotate the platen, an operating lever, a pawl on the lever for driving the gear to move the platen in line-space direction, a toothed wheel in firm connection with the platen, and means 40 movable by the operating lever into positive interlockment with the teeth of the last-mentioned wheel, to arrest the platen, upon a predetermined throw of the lever in line-space direction.

13. In a typewriting machine, a rotary platen, and means for effecting and determining a gross line-spacing movement thereof, comprising a gear connected to rotate the platen, an operating lever, a pawl on the 45 lever for driving the gear to move the platen in line-space direction, a toothed wheel in firm connection with the platen, an arm having a detent thereon, and means whereby the operating lever actuates the 50 arm to move the detent thereof into positive interlockment with the teeth of the last-mentioned wheel, to arrest the platen, upon a predetermined throw of the lever in line-space direction.

14. In a typewriting machine, a rotary

platen, and means for effecting and determining a gross line-spacing movement thereof, comprising a gear connected to rotate the platen, an operating lever, a pawl on the lever for driving the gear to move the platen in line-space direction, a toothed wheel in firm connection with the platen, a loosely-pivoted arm having a detent thereon, means whereby the operating lever actuates the arm, to cause the detent 70 thereof to be interlocked positively with the teeth of the last-mentioned wheel upon a predetermined throw of the lever in line-space direction, and a spring for disengaging the detent from the teeth when the operating lever is moved in return direction. 75

15. In a typewriting machine, a rotary platen, and means for effecting and determining a gross line-spacing movement thereof, comprising a gear fast to the platen, 80 another gear in mesh therewith, a ratchet-wheel fixed to the last-mentioned gear, an operating lever pivoted eccentrically with respect to the platen, a pawl on the lever engageable with the ratchet-wheel for movement of the latter in line-space direction, an arm loose on the axis of the operating lever, a detent on the arm, and means whereby the operating lever actuates the arm to move the detent thereof into positive interlockment 90 with the teeth of the first-mentioned gear, to arrest the platen, upon a predetermined throw of the lever in line-space direction. 95

16. In a typewriting machine, a rotary platen, and means for effecting and determining a gross line-spacing movement thereof, comprising a gear connected to rotate the platen, an operating lever, a pawl on the lever for driving the gear to move the platen in line-space direction, and means in 100 part on and fast to the platen-axle and in part movable by the operating lever to cause one of said parts to engage and hold the other of said parts, to arrest the platen, upon a predetermined throw of the lever in 105 line-space direction. 110

17. In a typewriting machine, a rotary platen, and means for effecting and determining a gross line-spacing movement thereof, comprising a gear connected to rotate the platen, an operating lever, a pawl on the lever for driving the gear to move the platen in line-space direction, and means for positively locking the platen against overthrow, comprising a stop loosely set in the path of 115 the lever to be picked up and carried by the latter to effective position, in which position the stop also serves to determine the throw of the lever. 120

18. In a typewriting machine, the combination with a platen-frame, a platen journaled therein, and a regular line-space mechanism for said platen, of platen-sweep mechanism comprising a ratchet, means operatively connecting the ratchet and platen, 125 130

a ratchet-operating handle having a one-way driving connection with the ratchet, an adjustable stop for determining a normal idle position of the handle, a spring for re-
5 turning the handle to said normal idle position independently of the ratchet, and means for adjusting the tension of said spring to correspond to the setting of the

adjustable stop to assure the full return of the handle to said adjustable stop in each of 10 the adjusted positions thereof without unnecessary force.
